CLAIM

The ornamental design for a dispenser mounting device, as shown and described.

DESCRIPTION

FIG. 1 is a top, left, front perspective view of a fourth embodiment of a dispenser mounting device embodying our new design;

FIG. 2 is a left elevational view thereof, the right elevational view being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

In a preferred embodiment, the nature of this product is a liquid dispensing device for dispensing liquids from the rim of a toilet.

The broken line representations in the views are for illustrative purposes only and form no part of the claimed design.
